ELECTRICAL SIGNALING SYSTEM

Amedee A. C. Heron, Paris, France, assignor to
International Standard Electric Corporation,
New York, N. Y., a corporation of Delaware

Application March 10, 1943, Serial No. 478,702
In France June 6, 1940

11 Claims. (Cl. 177—353)

1

The present invention relates to electric systems for automatic transmission of impulses of predetermined duration at set time intervals.

An object of the present invention is to provide a system of this character which is dependable and whose speed is vastly increased over that of systems now in use.

A further object of the invention is to provide a system which requires but a small number of control elements yet permits of a great number of combinations of time intervals at which impulses may be transmitted.

In brief, I accomplish these objects of the invention by the use of differential relays insuring rapid action and by such correlation of elements that the possible number of different time intervals between successive impulses increases manifold by the addition of merely a few control devices.

Thus, in the system described by way of example in the following specification, 32 different intervals may be obtained by means of but 10 relays (AA₁, AA₂, BB₁, etc.).

Moreover, by adding merely two more relays, it is possible to obtain 64 combinations and so forth, the number of combinations being doubled by each pair of relays added.

With these and other objects in view, as will become more apparent hereinafter, my impulse transmission control system is fully described in the following specification and illustrated, by way of example, in the accompanying drawing.

In the drawing, element MM designates a starting key, button or similar element operating circuit. Members C₁, C₂, C₃, C₄, C₅, C₁₀, C₁₅, C₂₀, C₂₅ and C₃₀ are control contacts in the branches of a holding circuit which may be opened and closed by means of any conventional switch or the like (indicated in each instance as a push button switch) which permits actuation of these contacts in any desired order. The action of key MM may of course be combined with that of each of control contacts C₁, C₂, C₃, etc.

Reference letters I_u designate the transmitting circuit over which the impulses are to be transmitted at certain time intervals. Key MM and control contacts C₁, C₂, C₃, etc., are connected (over circuits fully described hereafter) to the vibrator relays V₁, V₂, the holding relay I and the various differential relays AA₁, AA₂, BB₁, BB₂, CC₁, CC₂, DD₁, DD₂, EE₁, EE₂. These relays co-operate with the respective contacts placed opposite them, such as T₁, T₂, T₃, R₁, R₂, T_{1x}, T_{2x}, as shown in the drawing.

If it is desired to transmit impulses at intervals

of $\frac{1}{16}$ of a second, for instance, the following circuit is set up:

First, starting key or button MM is depressed and the switching device put in position C₁ to separate contact pieces C₁. When key MM is depressed, vibratory relay V₂ is energized. In its working position, relay V₂ attracts its contact T₁ and completes transmitting circuit I_u. As a result, an impulse is transmitted. At the same time, relay V₂ attracts its contact T₂ and closes the energizing circuit of vibrator relay V₁. When the latter is energized, it attracts its contact T₁ and opens the energizing circuit of relay V₂. Relay V₂ thereupon releases its contacts and returns to rest position. As a result, transmitting circuit I_u is interrupted at contact R₁ of relay V₂, while the circuit of relay V₁ is interrupted at its contact R₂ and relay V₁ releases its contacts and returns to rest position. By releasing its contacts, relay V₁ re-establishes connection between its contacts T₁, R₁, whereby the energizing circuit of relay V₂ is restored. Relay V₂ is thereupon re-energized, and the cycle of operations just described repeats itself; vibrator relays V₁ and V₂ are alternately energized and deenergized and this pulsation causes the transmission of an impulse over transmitting circuit I_u at given intervals.

It will be clear that vibrator relays V₁ and V₂ may be replaced by any other system or device (for example a cam and motor of known type) which will close a contact, such as contact T₁ of relay V₂, at given intervals.

If it is desired to transmit impulses at $\frac{1}{32}$ of a second intervals, for example, the switch is placed in position C₂, before key MM is depressed. When key MM is depressed, it produces pulsations by means of vibrator relays V₁ and V₂ as just described. When relay V₂ is energized for the first time, an impulse is transmitted over wire I_u due to the closing of contact T₁ of relay I. The following circuits are thereupon established: First circuit: ground, upper contact C₁, contact T₂ of relay V₁ (when the latter is energized), contact R₁ of relay BB₁, contacts C₂, winding of relay I, battery. Relay I, when energized, attracts its contact T₁ and opens control circuit I_u. This interruption of control circuit I_u thus occurs after transmission of the first impulse. Relay I then holds its contacts over the same circuit by means of its contact T₂. Second circuit: ground, contacts C₁ (in rest position), T₃ of relay V₁, R₂ of relay AA₁, lower windings of relays AA₁ and AA₂, battery. Third circuit: ground, contacts C₁, T₃ of relay V₁, T_{2x}

of relay AA₂, upper winding of relay AA₂, battery.

Differential relays AA₁ and AA₂ have their windings arranged in opposition. Therefore, when both windings of relay AA₂ are traversed by current, as above described, they act in opposition to each other, with the result that relay AA₂ is balanced and is not put into operation. Relay AA₁, on the other hand, of which but the lower winding is energized, attracts its armature which is placed into working position. However, as soon as relay V₁ becomes de-energized, the upper winding of relay AA₂ is no longer supplied with current (due to the return to normal of the contacts of relay V₁), and relay AA₂ is energized over its lower winding, in parallel with relay AA₁, via T₁ of AA₁, T₂ of I, contacts C₁ and ground.

When relay V₁ is now re-energized, differential relay BB₁ is energized over the following circuit: battery, lower winding of BB₁, R₂ of BB₁, T_{2x} of AA₂, T₃ of V₁, C₁ and ground. It holds then over its contact T₁. On the other hand, differential relay BB₂ remains inoperative, the same as explained in connection with relay AA₂, namely, both its windings being supplied, their opposed actions prevent the energization of the relay. Furthermore, relay AA₁, whose upper winding is fed over the same circuit, across T_{2x} of AA₂, returns to normal, the action of its lower winding being balanced by that of its upper winding. When relay V₁ releases its contacts again, relay AA₂, which was held over R₂ of relay AA₁, is de-energized. However, relay BB₂, whose upper winding is no longer supplied over T_{2x} of AA₂, is energized over: battery, lower winding of BB₂, T₁ of BB₁, T₂ of I, contacts C₁, and ground. Relays BB₁ and BB₂ are thus energized, and as a result the circuit of relay I is broken at contacts T₁ of BB₁ and T_{1x} of BB₂. Relay I is thus de-energized and releases its contacts. Inasmuch as at this moment relay V₁ is deenergized and relay V₂ is energized, an impulse is transmitted over wire I_u over contacts T₁ of V₂ and R₁ of I. Due to the fact that relay I has returned to normal, as just explained, its contact T₂ is open and the holding circuit of relays BB₁ and BB₂ is broken. Relays BB₁ and BB₂ thus likewise return to normal. As soon as relay V₁ is re-energized, the energizing circuit of holding relay I is restored and relay I is re-energized. Thus, the operating cycle of relays AA₁, AA₂, BB₁ and BB₂ is repeated and an impulse is transmitted at the end of each cycle. It will be clear that this operating cycle is repeated as long as starting key MM of the vibrator relay or the like is kept in operating position.

If it is desired to transmit impulses at intervals of $\frac{5}{6}$ of a second, for example, the following cycle of operations takes place:

First, the switch is brought into position C₅. Key MM is then depressed and the operation of relays V₁ and V₂ takes place as previously described, a first impulse being transmitted over transmitting circuit wire I_u when relay V₂ is energized. As soon as relay V₁ is energized, the holding circuit of relay I is completed over: battery, winding of relay I, lower pair of contacts C₅, R₁ of relay AA₁, T₂ of V₁, contacts C₁ and ground. Moreover, relay AA₁ is energized, over the following circuit: ground, contacts C₁, T₃ of V₁, R₂ of AA₁, lower winding of relay AA₁. Relay AA₂, whose two windings are fed, remains inoperative as previously described. When relay V₁ releases its contacts, relay AA₂ is ener-

gized, because its upper winding is no longer fed. When relay V₁ is energized for the second time, relay BB₁ is energized and relay AA₁ releases its contacts, as explained in the aforesaid example. Likewise, as soon as relay V₁ releases its contacts again, relay AA₂ releases its contacts, in turn, and relay BB₂ is energized. Relay I, however, remains in holding position over the following holding circuit: ground, contact C₁, T₂ of I, T₁ of CC₁ (or T_{1x} of CC₂), upper pair of contacts C₅, winding of relay I, battery. When relay V₁ is energized for the third time, relay A₁ is re-energized as before. When relay V₁ releases again, relay AA₂ is energized in its turn. When relay V₁ is now energized for the fourth time, relay BB₂ is energized again and relay AA₁ releases its contacts. Also, relay CC₁ is energized over: battery, lower winding of CC₁, R₂ of CC₁, T_{2x} of BB₂, T_{2x} of AA₂, T₃ of V₁, contacts C₁ and ground. When relay V₁ releases again, relays AA₂ and BB₂ release their contacts and relay CC₂ is energized. When relay V₁ is thereupon energized for the fifth time, relay A₁ is re-energized, while relays CC₁ and CC₂ remain in holding position.

Finally, when relay V₁ releases its contacts, and relay V₂ is energized, relay AA₂ is energized. At this moment, the holding circuit of relay I is broken, as follows: as to the lower pair of contacts of C₅, the circuit is broken at contact T₁ of AA₁ and contact T_{1x} of AA₂; and, as to the upper pair of contacts C₅, the circuit is broken at contact T₁ of CC₁ and contact T_{1x} of CC₂. Relay I thus returns to normal and brings about de-energization of relays AA₁, AA₂, CC₁ and CC₂ due to the opening of contact T₂ of I. On the other hand, relay V₂ is energized, and an impulse is transmitted over transmitting wire I_u.

The energizing circuit of relay I is restored by the return to normal of relays AA₁ and AA₂, CC₁ and CC₂. Relay I is re-energized when relay V₁ is energized again and the cycle of operations described repeats itself, an impulse being transmitted at the end of each cycle.

In the examples given above, transmission of impulses took place at intervals of $\frac{1}{10}$, $\frac{2}{10}$ and $\frac{5}{10}$ of a second. The accompanying drawing outlines the circuits for transmission of impulses at the following intervals: $\frac{1}{10}$ to $\frac{5}{10}$ of a second; and at $\frac{10}{10}$, $\frac{15}{10}$, $\frac{20}{10}$, $\frac{25}{10}$ and $\frac{30}{10}$ of a second. In each case, the cycle of operations is as already described, each new combination of contacts involving the energization of a group of differential relays or the return to normal of one or more of these relays.

It should be noted that the intervals mentioned in the foregoing specification are given merely by way of example without intention of limiting the invention thereto. Indeed, these particular intervals could be replaced by any other desired range of time intervals determining the pulsation frequency of the vibrator relays, or any other known equivalent device, without departing from the spirit and scope of the present invention. Similarly, the arrangement of the switching device and contacts could be modified so as to permit transmission of impulses at intervals representing multiples of the interval range chosen, same amounting, in the above given example, to one to thirty-two.

I claim:

1. In a system of the character described, a transmitting circuit, operating means intermittently opening and closing said transmitting circuit to transmit intermittent impulses over the

same, a holding circuit including a holding relay supplied thereby, a first holding contact disposed in said transmitting circuit and opened and closed by said holding relay, said holding circuit including a plurality of branches terminating in a common return line, a second holding contact disposed in said holding circuit and adapted to be opened and closed by said holding relay, contact means disposed in said return line and operated by said operating means to intermittently open and close said return line, switch contacts disposed in said branches, switch means adapted to actuate a plurality of switch contacts of different branches simultaneously, to connect said branches to or disconnect same from said return line, control circuits associated with said branches, the said second holding contact, and said contact means, said control circuits being interconnected and adapted to be energized in sequence, each control circuit including relays under the control of said operating means connected to be operable to open different respective branches of the holding circuit and thereby permit closing of the transmitting circuit only after energizing of the preceding control circuits, whereby, depending upon the actuation of said switch contacts, various sequences of control circuits may be connected to said return line.

2. In a system of the character described, a transmitting circuit, operating means intermittently opening and closing said transmitting circuit to transmit intermittent impulses over the same, a holding circuit including a holding relay supplied thereby, a first holding contact disposed in said transmitting circuit and opened and closed by said holding relay, said holding circuit including a plurality of branches terminating in a common return line, a second holding contact disposed in said holding circuit and adapted to be opened and closed by said holding relay, contact means disposed in said return line and operated by said operating means to intermittently open and close said return line, switch contacts disposed in said branches, switch means adapted to actuate a plurality of switch contacts of different branches simultaneously, to connect said branches to or disconnect same from said return line, control contacts associated with said branches and said return line, control circuits associated with said branches, the said second holding contact and said contact means, said control circuits including control relays adapted to actuate said control contacts, said control circuits being interconnected and adapted to be energized in sequence, each control circuit including relays under the control of said operating means connected to be operable to open different respective branches of the holding circuit and thereby permit closing of the transmitting circuit only after energizing of the preceding control circuits, whereby depending upon the actuation of said switch contacts, various sequences of control circuits may be connected to said return line.

3. In a system of the character described, a transmitting circuit, operating means intermittently opening and closing said transmitting circuit to transmit intermittent impulses over the same, a holding circuit including a holding relay supplied thereby, a first holding contact disposed in said transmitting circuit and opened and closed by said holding relay, said holding circuit including a plurality of branches terminating in a common return line, a second holding contact disposed in said holding circuit and adapted to be opened and closed by said holding relay, contact

means disposed in said return line and operated by said operating means to intermittently open and close said return line, switch contacts disposed in said branches, switch means adapted to actuate a plurality of switch contacts of different branches simultaneously, to connect said branches to or disconnect same from said return line, a pair of differential relays assigned to each branch, each differential relay having a pair of opposite windings and a feeding circuit therefor, a plurality of control contacts associated with said return line in the respective branches thereof and adapted to be operated by said differential relays, the latter being interconnected so as to be operative in sequence, each differential relay being under the control of said operating means connected to be operable to open different respective branches of the holding circuit and thereby permit closing of the transmitting circuit only after energizing of the preceding differential relays, whereby, depending upon the actuation of said switch contacts, various branches may be connected to said return line to control the sequence of the respective differential relays, the sequence of energization of the latter determining the time interval during which said holding circuit is closed and said transmitting circuit held open against closing by the operating means.

30 4. In a system of the character described, a transmitting circuit, operating means intermittently opening and closing said transmitting circuit to transmit intermittent impulses over the same, a holding circuit including a holding relay supplied thereby, a first holding contact disposed in said transmitting circuit and opened and closed by said holding relay, said holding circuit including a plurality of branches terminating in a common return line, a second holding contact disposed in said holding circuit and adapted to be opened and closed by said holding relay, contact means disposed in said return line and operated by said operating means to intermittently open and close said return line, switch contacts disposed in said branches, switch means adapted to actuate a plurality of switch contacts of different branches simultaneously, to connect said branches to or disconnect same from said return line, a pair of contact pieces connecting the terminal end of each branch to said return line, a cooperating contact disposed opposite the first contact piece of each pair, a pair of differential relays associated with each pair of contact pieces, each differential relay having oppositely arranged windings, a control circuit for each winding, the control circuits of the different windings including other relays under the control of said operating means connected to be operable to open different respective branches of the holding circuit and thereby permit closing of the transmitting circuit only after energizing of the preceding control circuit, conductive means connecting the first pair of differential relays to said contact means, intermediate contacts connected to said conductive means and the control circuits of said first pair of differential relays, the latter controlling said intermediate relays, whereby said control circuits are intermittently closed by said contact means and said branches disconnected in sequence according to the actuation of said switch contacts, whereby said holding circuit is closed and the transmitting circuit held open against closing by the operating means for such interval of time as is consumed for energization of the selected sequence of differential relays.

5. The system claimed in claim 4, in which the lower windings of each pair of differential relays are connected in parallel.

6. The system claimed in claim 4, in which the control circuit of the upper winding of the first differential relay of the first pair is connected to both lower windings of the second pair and the upper winding of the second relay of the second pair and so forth.

7. The system claimed in claim 4, in which the lower windings of each pair of differential relays are connected in parallel and the control circuit of the upper winding of the first differential relay of the first pair is connected to both lower windings of the second pair and the upper winding of the second relay of the second pair and so forth.

8. In a system of the character described, a transmitting circuit, operating means for intermittently interrupting said transmitting circuit to transmit impulses over same, a first holding contact in said transmitting circuit, a holding circuit, a relay adapted to be energized by said holding circuit, said holding relay controlling said first holding contact to open or close said transmitting circuit independently of said operating means, said holding circuit comprising a plurality of branches terminating in a single return line, a second holding contact disposed in said return line and controlled by said holding relay, interrupting means disposed in said return line and controlled by said operating means to intermittently open or close said return line, switch contacts for connecting and disconnecting the individual branches, switch means adapted to open or close a pair of control relays assigned to each branch, energizing circuits for said control relays, a return line common to all said branches and said energizing circuits; a second holding contact disposed in said return line and controlled by said holding relay to open or close said holding circuit, control contacts associated with said control relays and said return line, said control relays being adapted to successively act upon said return line through the respective control contacts in order to keep said holding circuit closed during work position of said operating means, the number of control relays energized depending upon the number and combination of switch contacts closed by said switch means, whereby said second holding relay will keep the holding circuit closed and said transmitting circuit open against closing by the operating means during a predetermined number of interruptions by said operating means, representing the interval of time corresponding to the position of said switch.

9. The system claimed in claim 1, in which said operating means comprises an operating circuit, a first relay energized by said circuit, a first cooperating contact disposed in said transmitting line and controlled by said first relay; an interrupter circuit, a second relay disposed in said interrupter circuit, a second cooperating contact disposed in said interrupter circuit and controlled by said first relay; a third cooperating contact disposed in said operating circuit and controlled by said second relay and a key to open and close said operating circuit, whereby in closed position of said key said transmitting circuit is intermittently opened.

10. The system claimed in claim 1, in which said operating means comprises an operating cir-

cuit, a first relay energized by said circuit, a first cooperating contact disposed in said transmitting line and controlled by said first relay; an interrupter circuit, a second relay disposed in said interrupter circuit, a second cooperating contact disposed in said interrupter circuit and controlled by said first relay; a third cooperating contact disposed in said operating circuit and controlled by said second relay, the latter cooperating with said contact means; said contact means comprising a pair of contacts, one of the latter being connected with said control circuits and the second of the latter contacts being connected to said return line; and a key to open and close said operating circuit, whereby in closed position of said key said transmitting circuit is intermittently opened.

11. In a system of the character described, a transmitting circuit, operating means for transmitting intermittent impulses over said transmitting circuit, a holding circuit including a holding relay, first holding contacts disposed in said transmitting circuit and controlled by said holding relay to open and close said transmitting circuit, said holding circuit comprising a plurality of branches terminating in a common return line, second holding contacts disposed in said return line and adapted to open and close the holding circuit; third holding contacts disposed in said return line and intermittently opened and closed by said operating means, switch contact associated with each branch, switch means adapted to open and close a plurality of switch contacts of different branches, simultaneously, to connect one or more of said branches to said return line in selected combinations; said third holding contacts, when closed by said operating means, close said holding circuit over a plurality of branches according to the position of said switch, causing closing of said first holding contacts, a plurality of control circuits associated with said branches and said second holding contacts to maintain the latter in closed position, said control circuits being interconnected and adapted to be closed independently by said third holding contacts and said second holding contacts, said control circuits being interconnected for operation in sequence, each control circuit including relays under the control of said operating means connected to be operable to open different respective branches of the holding circuit and thereby permit closing of the transmitting circuit only after energizing of the preceding control circuits, whereby said holding circuit remains closed interrupting transmission of impulses until the last control circuit of the sequence cut in by said switch has been energized, whereupon said holding circuit is broken, an impulse transmitted and the cycle of operations repeated.
